UNITED STATES PATENT OFFICE.

STANLEY A. HANSON, OF BARNESVILLE, GEORGIA.

UNDERGARMENT.

1,417,992.

Specification of Letters Patent. Patented May 30, 1922.

Application filed April 7, 1920. Serial No. 371,896.

To all whom it may concern:

Be it known that I, STANLEY A. HANSON, a citizen of the United States, residing at Barnesville, in the county of Pike and State 5 of Georgia, have invented a certain new and useful Improvement in Undergarments, of which the following is a full, clear, and exact description, reference being had to the accompanying drawings.

10 My invention has for its object the construction of a union undergarment wherein both the body portion and the inserted flaps to form the seat are so mutually arranged that there may be a minimum number of cutting operations and the entire article may be made from a single length of fabric with practically no waste. A further object is the provision of a garment thus economically constructed, having the desirable 15 features of a permanently closed crotch formed of a single thickness of cloth, and a non-gapping seat having ample fullness to permit of free movement, and which may be closed by a single button or its equivalent.

20 The invention will be more fully herein-after described, and the essential characteristics will be summarized in the claims.

25 In the drawings Fig. 1 is a plan of a

of tubular knit fabric in the usual manner. By cutting along the lines 13 and 14 the front and rear neck openings, respectively, of the finished garment may be produced, 60 while by cutting both thicknesses of the tubular fabric from the point 18 to the point 19 the sleeve openings 16 at the shoulders 17 may be made. The central lengthwise opening 20 in the front of the 65 completed garment, having finished edges adapted to be closed by buttons and button-holes, is provided by slitting the tubular fabric 10 from the point 21 down to the point 22, and by continuing the slit to the 70 point 23 the crotch opening 25 is provided for.

To form the leg portions 11 from the body cloth 10 diagonal cuts are made along the lines 23—24 and 28—29. The position and 75 direction of these lines of severance are specially selected to leave pieces on the outer sides adapted for use as flap inserts, as hereinafter explained. Between the point 29 and a point 30 above the waist line of 80 the garment the tubular fabric is slit leaving edges 34 to receive the flap inserts which are sewed in a manner hereinafter described. The portion 31 of the body cloth from the point 30 upward to the shoulders 85 around the neck opening 14 is left uncut and constitutes what is known as backrise.

As above mentioned, the waste portions from the body cloth 10 after cutting along the lines 23—24 and 28—29 to form the leg 90 portions 11 as above described are so shaped that they may be utilized in the construction of the seat flap inserts, which heretofore have required the cutting of extra cloth or fabric. As shown in Fig. 1 these portions 95 are triangular in shape and of unequal dimensions, the portion 35 being somewhat more than twice as wide as the portion 36. Figs. 6 and 5 show the wide and narrow flaps respectively, after they are unfolded. As shown also in Fig. 5, by cutting the portion 36 along the lines 37 and 38 the portions 39 and 40 may be removed, thus leaving the completed smaller flap 36 which is secured with the large flap 35 to the body 105 cloth 10 as hereinafter described.

In Figs. 7 to 11 the insert flaps 35 and 36 are shown sewed to the body cloth. With this construction there is provided a closed seat union suit with a single thickness of 110 material throughout the crotch, and with the large flap 35 overlapping the small one

30 length of tubular fabric for the production of a garment constructed according to my invention with the cuttings indicated. Fig. 2 is a transverse section on the line 2—2 of Fig. 1; Figs. 3 and 4 are front and rear 35 views of the body cloth of Fig. 1 when unfolded; Fig. 5 is a view of the smaller flap when unfolded and cut for uniting with the body cloth; Fig. 6 shows the larger flap unfolded; Fig. 7 is a fragmentary vertical 40 section through the crotch; Figs. 8 and 9 are fragmentary plan views in detail of the crotch and adjacent portions of the garment, as the same would appear were the garment split longitudinally on each side and 45 the front and rear halves of the upper or body portion spread out in a common plane with the inner sides of the leg portions extending at right angles thereto, Fig. 8 showing the outer flap broken away to dis- 50 close the small flap, and Fig. 9 indicating the two flaps in normal superposed position; and Figs. 10 and 11 are front and rear views, respectively, of the finished garment.

In the drawings, referring particularly to 55 Fig. 1, the numeral 10 designates the body of the garment which is preferably made

36 and held in closed position by a single button 45 or its equivalent. As shown in these figures the small flap or insert 36 is sewed to the rear portion of the body cloth 5 along the lines 51—52, 52—53 and 53—54, the edge 38 being attached along the line 51—52 slightly above the waistline, and the edge 37 along the line 53—54 at one leg seam adjacent to the crotch. The line 10 51—54 represents the open or unseamed edge of the small flap insert 36.

The large flap or covering cloth 35 is sewed to the edges 34 of the body cloth along the line 65—52, 52—60, 61—53, 53—54, and 15 54—65, thus forming a permanently closed crotch of a single thickness of material and overlapping the small flap thereby preventing gapping. The curved line 60—61 represents the free or unseamed edge of the large 20 flap 35, which may be removably closed against the body cloth by the single button 45.

With my improved construction having the bases of triangular shaped flap inserts 25 secured to the body cloth adjacent to the crotch and extending upwardly to a point above the waistline, the finished garment has ample elasticity and room for free seat and shoulder movement. The overlapping flaps 30 prevent gapping, while the desirable features of a single thickness of cloth at the crotch and the one-button fastening for the outer flap are retained. By cutting the fabric as above described, whereby the waste 35 from the body cloth may be utilized as the flap inserts, a decided saving in the cost of material is effected as well as a reduction in the expenditure of time and labor in cutting such flaps from extra cloth in the usual 40 manner.

My invention includes both the garment herein illustrated and the method above described by which it may be economically made.

Having thus described my invention, I 45 claim:

1. The method of constructing a union undergarment comprising taking a length of flattened tubular fabric, cutting unequal 50 triangular portions from opposite sides thereof leaving a body cloth having leg portions, flattening said tubing along creases spaced 90° from the original ones, sewing together the adjacent edges of said leg portions, and inserting said triangular portions 55 as flap inserts in the rear of the body cloth.

2. The method of constructing a union undergarment from a length of tubular knit fabric comprising the cutting of two triangular pieces of different dimensions from 60 opposite sides of the tube, constituting the body cloth, said triangular pieces having an

extent longitudinally of the tube substantially equal to the extent of the legs to be formed, sewing together the edges thus 65 formed to constitute the legs, slitting the tube for a portion of the way up the center of the back, and the insertion of the triangular pieces between the leg portions and the edge of the slit in the back to form 70 overlapping seat flaps.

3. The method of constructing a union undergarment comprising taking a length of fabric, forming a body portion and leg portions therefrom by the removal of unequal 75 sized triangular flaps from the sides, inserting the smaller flap between the body portion and one of the leg portions, and stitching it thereto with one edge left unseamed, and stitching the larger flap to the 80 body portion and to both leg portions with such flap overlapping the smaller flap and with a central portion only of one edge remaining unseamed, and stitching edges, formed by cutting out the flaps, together to 85 form legs.

4. In the construction of a union undergarment having a body portion, leg portions formed therefrom by the removal of a triangular flap from each side, said flaps having different widths of base, the smaller flap being inserted between the body portion and one of the leg portions and stitched thereto with one edge left unseamed, the larger flap being stitched to the body portion and to both leg portions and overlapping the smaller flap, with a portion only of one edge remaining unseamed, and a single fastening means between said unseamed edge and the body portion being provided. 90

5. The construction of union undergarments from tubular fabric, comprising the formation of legs for the body portion thereof by the removal of triangular portions co-extensive longitudinally with the leg portions and the utilization of one of such triangular portions by securing it in a flaring opening at the rear of the body portion and extending it to the front to form the crotch closure. 95

6. The method of making undergarments which comprises creasing a tubular fabric along two edges, making two rectilinear cuts intersecting the end and one creased edge of said fabric, one of said cuts being made at a greater inclination to the end than the other cut, sewing the edges so formed on opposite sides of the fabric together to form the legs of the garment, and utilizing the portions cut out to form a seat flap. 110

In testimony whereof, I hereunto affix my signature.

STANLEY A. HANSON.
